CLAIM

The ornamental design for a mounting device, as shown and described.

DESCRIPTION

FIG. 1 is a front perspective view of the mounting device of the present design.

FIG. 2 is a back-side perspective view of the mounting device of the present design.

FIG. 3 is a front view of the mounting device of the present design.

FIG. 4 is a back view of the mounting device of the present design.

FIG. 5 is a side view of the mounting device of the present design.

FIG. 6 is a top view of the mounting device of the present design.

FIG. 7 is a bottom view of the mounting device of the present design.

FIG. 8 is a disassembled front perspective view of the mounting device of the present design.

FIG. 9 is a disassembled back perspective view of the mounting device of the present design.

FIG. 10 is a disassembled front view of the mounting device of the present design.

FIG. 11 is a disassembled back view of the mounting device of the present design.

FIG. 12 is a disassembled side view of the mounting device of the present design.

FIG. 13 is a disassembled top view of the mounting device of the present design; and,

FIG. 14 is a disassembled bottom view of the mounting device of the present design.
